FLOATING-SEAL COMMUTATOR

Willard L. Wright, Pittsburgh, Pa., assignor to
 Westinghouse Electric Corporation, East Pittsburgh, Pa., a corporation of Pennsylvania

Application January 21, 1949, Serial No. 71,845

3 Claims. (Cl. 171—321)

1

The present invention relates to commutators for dynamo-electric machines, and more particularly to commutators of the V-ring type. My invention was particularly designed for a railway-type traction-motor, but its general principles are applicable to other types of dynamo-electric machines.

More particularly, the present invention relates to a novel method and means for providing a seal which will not allow dirt or foreign matter to get into the V-ring assembly in such manner as to cause an electrical short between the bars of the commutator. Usually, such a seal is provided by causing the clamping V-rings to enter far enough into the V-grooves in the ends of the commutator-bars, so as to make a wedging-contact, pressing radially outwardly on the ends of the bars, in addition to the arch-binding contact which is made by the inclined inner surface of the clamping-V-rings, pressing against the corresponding surfaces of the V-grooves in the bars. The necessity for providing this wedging-action, in order to seal the upper inclined surface of the V-rings, and the upper inclined surfaces of the V-grooves of the bar, so as to prevent the entrance of dirt, has heretofore resulted in considerable difficulty, due to the non-uniformity of the thickness of the insulating V-rings which have to be provided, thus resulting in a variation in the outward pressure which is exerted against the extreme ends of the commutator-bars, causing non-uniform deflection of these ends or overhanging portions of the commutator-bars, producing a rough surface for the commutator-brushes to slide upon.

The sealing-difficulties of V-ring commutators have often been attacked heretofore, but are still with us. To mention only two means which have been adopted heretofore, to combat the sealing-trouble, reference may be made to a Dick Patent 2,351,021, and a Mueller Patent 2,426,042. In the Dick commutator, the wedging-action of the clamping V-ring was omitted altogether, resulting in a small open space between the upper inclined surface of the clamping-V-ring and the upper inclined surface of the V-grooves in the commutator-bars, and this small open space was closed by a kind of resilient sealing-means which was applied externally around the insulating V-rings at each end of the commutator-bar assembly. In the Mueller commutator, a special construction was provided, in which both the clamping V-ring and the V-groove of the commutator-bars were provided with cylindrical,

2

or non-inclined surfaces, which could be sealed without any wedging-action.

The object of my present invention is to provide a novel form of V-ring seal, making it possible to use a commutator-construction which is entirely arch-bound, without any wedging-action of the clamping V-rings, by using either a resiliently expanding ring or a floating ring, which is provided in a groove in the clamping-V-ring, near the end of the associated V-groove of the commutator-bars, forcing the associated insulating V-ring outwardly into a dirt-sealing engagement with the outer surface of the associated V-groove at the entrance to said V-groove.

15 With the foregoing and other objects in view, my invention consists in the combinations, parts, means, methods, processes and general and specific forms of embodiment, hereinafter described and claimed, and illustrated in the accompanying drawing, wherein,

Figure 1 is a fragmentary longitudinal sectional view of the commutator-end of a dynamo-electric machine embodying my invention, and

Fig. 2 is a similar view of one end of the commutator, showing another form of embodiment which is in some respects preferred.

I have shown my invention applied to a commutator-type dynamo-electric machine in the form of an alternating-current railway-traction motor, comprising a stator-member 1 and a rotor-member 2, the latter being mounted on a shaft 3 and carrying a substantially pre-seasoned V-ring commutator-assembly 4 in accordance with my present invention. The commutator-assembly is made up of a number of copper commutator-bars 5, separated by mica or other insulating bars 6, the two kinds of bars being of similar size and shape, except that the insulating bars commonly project back about $\frac{1}{8}$ of an inch behind the commutator-bars, as indicated by the numeral 6, that is, the mica bars 6 are longer than the copper bars 5. The bars 5 and 6 are provided with V-grooves 7 in the ends thereof, said V-grooves having inclined inner, arch-binding surfaces 8, usually at a 30° angle, and outer surfaces 9, usually at a 6° angle.

The V-grooves 7 are insulatingly engaged by clamping V-rings 11, usually of steel, having inner conical surfaces 12, inclined at an angle matching the inner archbinding surfaces 8 of the V-grooves, and outer surfaces 13, inclined at an angle usually matching the outer surfaces 9 of the V-grooves. The insulating engagement is provided through the intermediary of insulating V-rings 14, preferably made of sheet-mica of sufficient thickness

to withstand the maximum voltage which is applied to the commutator-member. The relative dimensions of the clamping V-rings and the V-grooves are such that the groove-entering portions of the insulated inner, conical surfaces 12 of the clamping V-rings tightly engage the respective inner, arch-binding surfaces 8 of the V-grooves, with the insulating V-rings 14 interposed in between, and with the insulated outer surface 13 of each clamping V-ring spaced out of pressure-transmitting engagement as indicated at 15, with respect to the outer surface 9 of the associated V-groove. The outer surface 13 of each V-ring 11, with its superposed portion of the mica V-ring 14, also has an extended portion 16 which extends out of the V-groove, beyond the end of the commutator-member, and which is cemented or otherwise secured to the corresponding portion of the clamping V-ring 11, which may be a slightly raised surface 19 as shown.

In accordance with my present invention, I not only provide the clearance-space 15 between the outer surfaces of the insulated clamping V-rings and the V-grooves, but I also provide means for flexibly sealing the entrance to each of these clearance-spaces 15, against the accidental entry of foreign matter thereto. This sealing-means may take any one of several different forms, two of which are illustrated in the accompanying drawing.

As shown in the drawing, I provide the outer inclined surface 13 of one or both (preferably both) of said clamping V-rings 11 with a groove 21 therein, near the end of the associated V-groove 7 of the commutator-bars 5, and I use this groove 21 to seat a self-adjusting ring, which is shown in Fig. 1 as a resiliently expanding ring 22, which is disposed in said groove, for forcing the associated insulating V-ring 14 out into dirt-sealing engagement with the outer surface 15 of the associated V-groove 7, at the entrance 23 to said V-groove. This resiliently expanding ring 22 may be made either of rubber or a rubber-like composition, or it may be formed of high-tensile steel in such a curve that when it is compressed in the groove and assembled with the commutator-bars, the ring will be round and will exert a uniform radial force against the underside of the insulating V-ring 14, and hence against the ends of the commutator-bars 5, similar to a piston-ring in a piston-engine.

The operation of my invention, as shown in Fig. 1, is at once apparent. My clamping V-rings 11 engage the commutator-bars 5 with only an arch-binding force which is exerted between the two inclined surfaces 12 and 9, through the intermediary of the interposed insulating mica V-ring 14. The clamping V-ring 11 does not enter into any wedging engagement with the V-groove 7 of the commutator-bars 5, and hence there is no difficulty due to unequal or excessive outward pressure against the extreme ends of the V-grooved commutator-bars. The resiliently expanding ring 22, on the other hand, exerts a gentle and absolutely controllable force, just enough to safely close the opening between the top of the mica V-ring 14 and the top inclined surface 9 of the V-groove 7 in the commutator-bars 5. In assembling the commutator-structure, it is a simple matter to hold the resiliently expanding ring 22 compressed, if necessary, by a simple encircling tool (not shown), while forcing the insulation-covered clamping V-rings 11 into clamping-engagement with the V-grooves 7 in the two ends of the commutator-bar assembly.

In the form of my invention shown in Fig. 2, the self-adjusting ring 22 is a solid steel ring 22' which has a loose fit in the groove 21, so as to provide clearance so that the loose ring 22' may assume an eccentric position in the groove 21, or it may assume a not-quite-circular shape, when necessitated by any non-uniformity in the thickness of the mica V-ring 14. Thus, I obtain the sealing ability of a V-bound commutator, without the chance of excess pressure on the 6-degree copper overhang surface 9, in a commutator which is substantially entirely arch-bound.

An outstanding advantage of the solid loose ring 22' of Fig. 2, over the expanding ring 22 of Fig. 1, is that the solid ring 22' is much stronger, so that the commutator-bars 5 will withstand an appreciable blow on their overhanging ends, without bending at these ends. This is a decided advantage over a purely arch-bound commutator, which must be handled very carefully in order to prevent damage to the overhanging ends of the copper bars.

In Fig. 2, also, by way of illustration, the end of the mica V-ring 14, which overlies the raised ledge 19 of the clamping V-ring 11, is held down, against centrifugal force, by string-binding 24, which is the preferred securing-means.

I claim as my invention:

1. A commutator-cylinder for a dynamo-electric machine, said commutator-cylinder comprising a plurality of commutator-bars having V-grooves in the ends thereof, said V-grooves having inclined inner, arch-binding surfaces; insulating V-rings; clamping V-rings having inner, conical surfaces tightly engaging the inner, arch-binding surfaces of the V-grooves, with the insulating V-rings interposed in between; the insulation-covered outer surface of one or both of said clamping V-rings being spaced out of pressure-transmitting engagement with respect to the outer surface of the associated V-groove; said outer surface of said one or both of said clamping V-rings having a groove therein near the end of the associated V-groove; and a self-centering ring, disposed in said groove, for forcing the associated insulating V-ring out into a dirt-sealing engagement with the outer surface of the associated V-groove at the entrance to said V-groove.

2. A commutator-cylinder for a dynamo-electric machine, said commutator-cylinder comprising a plurality of commutator-bars having V-grooves in the ends thereof, said V-grooves having inclined inner, arch-binding surfaces; insulating V-rings; clamping V-rings having inner, conical surfaces tightly engaging the inner, arch-binding surfaces of the V-grooves, with the insulating V-rings interposed in between; the insulation-covered outer surface of one or both of said clamping V-rings being spaced out of pressure-transmitting engagement with respect to the outer surface of the associated V-groove; said outer surface of said one or both of said clamping V-rings having a groove therein near the end of the associated V-groove; and a resiliently expanding ring, disposed in said groove, for forcing the associated insulating V-ring out into a dirt-sealing engagement with the outer surface of the associated V-groove at the entrance to said V-groove.

3. A commutator-cylinder for a dynamo-electric machine, said commutator-cylinder comprising a plurality of commutator-bars having V-grooves in the ends thereof, said V-grooves having inclined inner, arch-binding surfaces; insulating V-rings; clamping V-rings having inner,

conical surfaces tightly engaging the inner, arch-binding surfaces of the V-grooves, with the insulating V-rings interposed in between; the insulation-covered outer surface of one or both of said clamping V-rings being spaced out of pressure-transmitting engagement with respect to the outer surface of the associated V-groove; said outer surface of said one or both of said clamping V-rings having a groove therein near the end of

the associated V-groove; and a loosely fitting solid ring, disposed in said groove, for forcing the associated insulating V-ring out into a dirt-sealing engagement with the outer surface of the associated V-groove at the entrance to said V-groove.
